UNITED STATES PATENT OFFICE.

GEORGE SIMPSON, OF RICHMOND, AND JOHNSTON R. GORDON, OF NEW YORK, N. Y.,
ASSIGNORS TO SIMPSON-GORDON PATENTS, INC., OF NEW YORK, N. Y., A CORPO-
RATION OF NEW YORK.

BILGE TUNNEL FOR SHIPS.

Application filed April 26, 1920. Serial No. 376,583.

To all whom it may concern:

Be it known that we, GEORGE SIMPSON and JOHNSTON R. GORDON, both citizens of the United States, residing in the borough 5 of Richmond, county of Richmond, and State of New York, and borough of Manhattan, city, county, and State of New York, respectively, have invented certain new and useful Improvements in Bilge Tunnels for 10 Ships, of which the following is a specification.

This invention has reference to ship's construction and, particularly, to the shaft tunnels thereof, or so-called bilge tunnels, which 15 are utilized for inclosing the propeller shafts.

It is an object of our invention to so constrict the shaft tunnels as to enable them to be used for the housing of the propeller 20 shafting, and also for the carriage of liquid fuel, feed water, water ballast or for other useful purposes; and to so construct the shaft tunnels at the bilge of the vessel as to enable a part at the outboard side, now 25 usually wasted or not utilized, to be utilized for ballast, stowage or other useful purposes, and to so connect the tunnels in the opposite bilges as to enable inspection of the shafting and bearings on both sides of the ship 30 without leaving the tunnels, and provide for the safety of the inspector, in case of accident, by the provision of a means of escape from the tunnels or shaft compartments, as will be hereinafter described.

Our invention is disclosed in the drawings 35 wherein Figure 1 is a cross-section of a vessel having our invention embodied therein; Figure 2 is a hold plan, on a similar scale, of the vessel shown in Figure 1; Figure 3 is a section, enlarged, substantially on the 40 line 3—3 of Figure 2; and Figures 4 and 5 show, respectively, alternative forms of compartments adapted for the protection of the shafting and for stowage, according to 45 our invention.

In Figures 1, 2 and 3 a vessel is conventionally shown, the same being of the cargo-carrying type, details of which have been omitted because not pertaining to our in- 50 vention. The numeral 1 indicates the watertight space formed by the bilge tunnel structure on both sides of the ship and through which the propeller shafting 2 is carried. The forward end of the tunnel or compart- 55 ment 1, on both sides of the ship, is pro-

vided with a watertight door 3, which may be set to slide either horizontally or vertically, and which will be operated mechanically or by hand, as may be desired, the said doors being only conventionally shown, 60 because details of construction are not a part of our present invention, it being only necessary to indicate watertight doors at the forward ends of the compartments or tunnels. As shown in Figure 2, the compartments 1, 65 through which the shafts 2 extend, are connected at their rear ends by a passage 4, so that the inspector may pass from one compartment or tunnel to the other without retracing his steps. Leading up from and 70 out of the cross passage 4 is a ladder 5 constructed in a casing or escape trunk 6 terminating in a closure or housing 7 on the deck having an exit closed by a door 8, and, at its top, having applied thereto the cowl 75 ventilator 9. The closure structure is only conventionally shown, since details thereof may be varied considerably and do not specifically pertain to our invention. It will be understood, however, that the trunk 6, 80 in which the ladder is constructed, is watertight and substantial and constitutes a medium of entrance to the passageway 4 and tunnels 1, as well as a medium of escape 85 from and ventilation for the cross passage 4 and compartments 1. The inner or hold walls 10 of the compartments 1 are formed 90 of steel plating supported by and connected to the tunnel framing 11 in any approved manner consistent with strength, simplicity 95 and economy. Longitudinally, the compartments 1 are partitioned so as to provide the outboard storage space, tank or compartment 12, as in Figures 1 and 2, the partition being formed by the oil and watertight fore 100 and aft bulkhead 13 suitably braced and supported by uprights 14, which also aid in supporting the tunnel framing 15 and top steel plating 16. The bulkhead 13 may extend throughout, or only a part of, the compartment space 1, and may be straight or curvilinear in outline. As shown in Figure 2, the forward end wall 17 of the compartment 12 is constructed at a short distance within the end wall of the compartment 1, giving ample space for the entrance of the 105 inspector and such manoeuvering as he may find necessary during the course of his duties. It will also be seen, viewing Figure 2, that the compartment 12 terminates at a con- 110

siderable distance forward of the rear cross passage 4, thus giving ample space between the narrowing sides of the vessel and the shafting for free movements of the inspector. Details of construction having reference to piping oil, ballast, etc., into the compartments 12 have not been shown, in order to avoid complications and also because the same do not pertain to our invention. Corner brackets 18 may be applied where necessary, together with floor or base angles 19, for strengthening purposes, and for support of the walls or plating.

The machinery compartment is indicated at 20, the engines at 21, the latter being conventionally shown, the stern tubes at 22, propellers at 23, and the hold of the vessel at 24.

Obviously, the compartments 12 could be made as spacious as desirable both by lengthening the same and by changing the form or location of the bulkhead 13, this depending upon the requirements of the shafting 2 or the space required or desired in the tunnel or compartment 1 therefor. In Figures 4 and 5, we have shown alternative forms which increase the stowage capacity of the compartments 12 and, in a measure, reduce the size of the tunnel compartments without restricting the freedom of the inspector or the space in which he operates. In Figure 4, the space enclosed at the bilge for the shafting and for stowage purposes is shown as covered by the inclined top wall 25 and inclined side or inboard wall 26, the two being connected at an obtuse angle. The framing is indicated at 27, the fore and aft bulkhead by 28, its framing at 29, and other supporting angles, brackets, etc., generally indicated at 30. The base angles, shafting and compartments in this form are indicated as in Figure 1. In Figure 5 the top wall plating 31 is shown downwardly inclined, while the inboard wall plating 32 is vertically disposed, the two walls being braced by the framing 33. The fore and aft bulkhead is indicated at 34 with framing 35; and other framing, brackets and angles are indicated by 36. The base angles, compartments and shafting in this figure are indicated as in Figure 1.

It will now be understood that our invention particularly has reference to the utilization of the waste space in vessels outboard of the shaft tunnel in the bilge, and to the conversion of the shaft tunnel into a bilge compartment for ballast and storage purposes. We have thus eliminated and utilized a vast area of waste space, converted the bilge, or shaft tunnel wastage, into a useful ballast tank and storage space, and have avoided infringing in any way upon the functions, advantages, merits and capacity of the shaft tunnel, and avoided encroaching in any particular upon the normal hold of the vessel. The many advantages for this

construction and improvement will be obvious to those skilled in the art.

We claim as our invention:

1. A ship having shaft tunnels in its opposite bilges extending from the machinery compartment to near the stern of the vessel, said tunnels being connected by a cross passage, and the latter having an escape trunk and ventilator leading to a deck of the vessel.

2. A ship having the entire bilge space between the engine room and stern tubes formed into a shaft tunnel by a fore and aft bulkhead, said tunnel being closed at its forward end by a transverse bulkhead having a door accessible from the engine room; and a ballast or storage compartment built up within the shaft tunnel by transverse bulkheads connected by a fore and aft bulkhead, all of which are independent of the shaft tunnel bulkheads.

3. A ship having the entire port and starboard bilge spaces between the engine room and the stern tubes formed into shaft tunnels by fore and aft bulkheads, each of said tunnels being closed at its forward end by a transverse bulkhead having a door accessible from the engine room; a ballast or storage compartment built up within each tunnel by transverse bulkheads connected by a fore and aft bulkhead, all of which are independent of the shaft tunnel bulkheads; said tunnels being connected at their after ends by a passage extending transversely of the ship, whereby inspection of shafting in both tunnels can be made without leaving the tunnels.

4. A ship having a machinery space; shaft tunnels extending along the entire bilge of the ship from said space to the stern tubes; means of entrance to said tunnels from said space; a water and oil tight storage compartment formed in each of said tunnels and having one fore and aft side formed by the side of the ship and its other fore and aft side formed by a bulkhead independent of the inboard side of the tunnel, and having its fore and aft ends closed by bulkheads remote from the tunnel ends.

5. A ship having a machinery space; shaft tunnels extending therefrom along the bilges of the vessel; means of entrance to said tunnels from said space; a stowage compartment formed in each of said tunnels having one fore and aft side formed by the side or shell of the vessel and its other fore and aft side by a bulkhead independent of the inboard side of the tunnel, and having its fore and aft ends closed by bulkheads independent of the tunnel ends, said tunnels being connected at their after ends by an athwartship passage open at a deck of the vessel, said passage having means of egress therefrom extending to said deck.

GEORGE SIMPSON.
JOHNSTON R. GORDON.
